PRESSURE REDUCING VALVE

Harry G. Bissell, Lebanon, Ohio, assignor to Jordan Regulator Corporation, Lebanon, Ohio

Application July 23, 1948, Serial No. 147,725

Term of patent 14 years

(Cl. D78—1)

To all whom it may concern:

Be it known that I, Harry G. Bissell, a citizen of the United States, residing at Lebanon, in the county of Warren and State of Ohio, have invented a new, original, and ornamental Design for a Pressure Reducing Valve, of which the following is a specification, reference being had to the accompanying drawings, forming part thereof.

Fig. 1 is a perspective view of a pressure reducing valve showing my new design. That side of the valve not shown in the drawing is the same as the side shown.

Fig. 2 is a bottom view of the pressure reducing valve of Fig. 1.

Fig. 3 is an end view of the valve of Fig. 1.

I claim:

The ornamental design for a pressure reducing valve, as shown and described.

HARRY G. BISSELL.
